SPLASH GUARD FOR USE ON SHOE HEELS

Clarence F. Hoover and Joseph Nissley,
Harrisburg, Pa.

Application January 4, 1949, Serial No. 69,094

3 Claims. (Cl. 36—70)

1

This invention relates to certain new and useful improvements in what have become to be known as splash shields and guards of a type attachable to the heel of a shoe and, obviously, designed to prevent mud and water from being undesirably splashed, during rainy weather, on the wearer's shoes, stockings and adjacent apparel.

As the opening statement of the invention implies, guards used for the same purposes are of many and varied forms and usually involve the use of a visor-like apron, which extends rearwardly from and at a suitable angle to the heel and means whereby same is readily applicable and removable. In carrying out the principles of the present invention, we provide a construction which is possessed of appreciable refinements, structural distinctions and other worthy characteristics which, it is submitted, contribute in providing an effective anti-splash guard or shield.

In reducing to practice the preferred embodiment of our anti-splash shield, we provide a resilient U-shaped wire frame whose limbs provide grips and serve to partly hold the shield in place, the shield being of sheet plastic or equivalent substantially waterproof material and being novel in that it is provided around its forward heel conforming edge with a flashing-like rubber or equivalent adapter which facilitates shedding and drainage of water.

Novelty, in addition to the above, is predicated upon the stated protective shield and prop or bracing means associated therewith, the lower portion of the prop having an additional heel grip and the prop including an accommodation spring which allows the prop to take the proper angle in relation to the heel and shield for effectively maintaining the latter in place.

Other objects and advantages will become more readily apparent from the following description and the accompanying illustrative drawings.

In the drawings:

Figure 1 is a side elevational view of a conventional type shoe with a splash guard, constructed in accordance with this invention, attached to the heel of a shoe.

Figure 2 is a section on the line 2—2 of Figure 1, looking in the direction of the arrows.

Figure 3 is a cross section on the line 3—3 of Figure 1, looking in the direction of the arrows.

Figure 4 is a perspective view of the anti-splash shield removed from the heel.

Referring now to the drawings by distinguishing reference numerals, the protector shield, as

2

a unitary part of the assemblage, is denoted by the numeral 6 and is constructed to minimize the likelihood of the shoes and stockings being splattered with mud and muddy water while one is walking in the rain or on muddy surfaces whether raining or not. As before indicated, the shield unit is made up of a substantially U-shaped resilient wire whose bight portion is denoted by the numeral 7 and whose arms or limbs are denoted by the numerals 8, said arms terminating in suitably shaped eyes 9 which function as grips and are adapted to embrace substantially diametrically opposite side surfaces of the shoe heel A. Incidentally, the shoe is broadly denoted by the reference letter B. A covering of sheet material, plastic, rubber or the like is fitted on and secured tautly to the frame to provide the anti-splash shield 10. The covering includes extensions or sleeve portions 11 which substantially enclose the arms 8 and prevent the latter from marring the surfaces of the heel. The forward crotch portion of the covering is fashioned to conform to the general contour of the heel and is provided with a rubber strip of flashing-like form denoted by the numeral 12 and conformable, in practice, to the heel. The surface 13 may be suitably contoured to facilitate draining the collected water from the shield to opposite sides of the heel in a substantially obvious manner.

The brace means referred to is denoted, in a general way, by the numeral 14 and comprises a rigid stub 15 forming the upper portion and a complemental longer section 16. These sections are joined together by an intervening spring 17 which constitutes an adapted and allows the part 16 to angle in respect to the part 15 so that the brace means 14 may accommodate heels of different degrees of slant and curvature, etc. The lower end of the prop member 16 terminates in an eye 18 which is connected with a U-shaped heel grip which is springy and denoted by the numeral 19. It comprises a spring wire of U-shaped form 20 and a rubber or equivalent covering 21. The tension of the end portions is such as to effectively grip opposite sides of the heel. Thus, by having the hinged eye connection between 14 and 19, and the flexible spring connection between 15 and 16, all of the elements are permitted to angle in respect to each other to accommodate changing conditions.

We would stress the provision of a main U-shaped member at the top carrying a covering and providing the shield and an auxiliary U-shaped member at the bottom embracing the heel

and an intervening prop-like stabilizer or brace made up of yieldably connected sections. In addition, we stress the provision of the flashing strip 12 with its curvate surfaces 13 which coact in improving the drainage facilities of the shield 6.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention, what is claimed as new is:

1. In a splatter guard for shoe heels, an apron-like shield including a resilient U-shaped member having springy limbs to partially embrace the heel, the crotch portion of said shield being rounded out to conform to coacting surfaces of said heel, a rubber flashing fitted into said crotch and coacting with the latter in providing an effective seal and assisting in shedding water from the shield, a U-shaped grip adapted to partially embrace a lower portion of said heel, and brace means interposed between and connected with the U-shaped member of said shield and said

- 20 2. In a heel anti-splattering shield attachment of the class described, a shield, a U-shaped grip 5 adapted to partly embrace the heel, and brace means between the U-shaped member and shield embodying coacting members, and a coiled spring connecting adjacent inner ends of the members to one another.
- 10 3. As a new article of manufacture, an attachment for a shoe heel, a U-shaped frame having its arms terminating in gripping members, a covering for said frame, and an arcuate flashing strip associative with the covering, a U-shaped heel grip, prop members connected one to the U-shaped frame and the other to the heel grip, and a coiled spring connecting said prop members one to the other.
